UNITED STATES PATENT OFFICE

WILLIAM K. PORTER AND HARRIS D. BURTON, OF PITTSBURGH, PENNSYLVANIA

VANITY DRESSER

Application filed July 10, 1928. Serial No. 291,657.

This invention pertains to articles of furniture and more particularly to what are known as vanity dressers, said dressers being adapted to serve for use other than as dressers where restricted space is a limiting factor.

In the present mode of living, there are many people who, by choice or by reason of necessity, live in one or two rooms or in an apartment. These apartments, as a rule, are small and restricted, with the result that it is very difficult to find space enough for all the necessary articles of furniture without overcrowding the apartment.

An object of this invention is to provide a novel vanity and dressing table which, when not in use as such, may be used as an ordinary table, said dressing table preferably having a bench fitting snugly underneath the same thereby making a very compact arrangement which is especially desired in the small apartments mentioned above where its daily dual usefulness and economy of space would be appreciated.

A further object of this invention is to provide a top for the table which may be locked in a position, by a special form of hinge, said hinge forming a special feature of this invention, to bring multiple mirrors located beneath the top into use, and allow ready access at all times when in this position to all the articles used in the preparation of the toilet, thereby making it possible to prepare the toilet in less time than when using the ordinary type of vanity dresser where the articles are contained in individual drawers.

Other objects and advantages of the invention will be hereinafter set forth and the novel features thereof defined by the appended claims.

In the drawings:

Figure 1 is a front elevation of the vanity dresser ready for use as such, with the top raised and bench in position.

Figure 2 is a front elevation of the vanity dresser in closed position for use as a table, the bench being nested under the table to provide free space around it.

Figure 3 is a top plan view of the dresser

with the top raised exposing the compartments containing the toilet articles.

Figure 4 is a transverse sectional view of the body portion of the dresser on line 4—4 of Fig. 3.

Figure 5 is an enlarged vertical sectional view taken on line 5—5 of Fig. 4, parts being broken away.

Figure 6 is an enlarged detail view of the supporting bracket for the top, on the operating side of the dresser, certain of the parts being shown in section.

Figure 7 is an enlarged detail view of the supporting bracket on the opposite side of the dresser.

Figure 8 is a fragmentary vertical sectional view through the lower portion of the top supporting bracket, the dotted lines showing the parts in relaxed position.

Figures 9 and 10 are sectional views on lines 9—9 and 10—10 of Figure 8 respectively.

Figure 11 is a vertical sectional view through the spring latch for holding the side mirrors in closed position.

Figure 12 is a sectional view on line 12—12 of Figure 11.

Figure 13 is a detail sectional view of the resilient clip for holding the bracket operating lever.

Like numbers refer to like parts in the several figures of the drawing.

In Figure 1, A denotes a vanity dresser comprising a body portion B, supported by suitable legs C so positioned as to enable the bench D to be fitted beneath the dresser when not in use, said body portion being provided with a top E having hinged side mirrors F attached to its under side. This body portion encloses partitioned compartments B' in which articles for toilet use are kept, said compartments having a base B'', which is preferably inclined to render the toilet articles more accessible.

Beneath the top E is located a large center mirror 1 against which the side mirrors are adapted to be swung on ornamental hinges 2 and to be retained in such closed position by the latch 3. The top is connected to the body portion by suitable hinges 4 and may

be locked in an upright position by supporting brackets 5, said supporting brackets being pivoted to the top at 5^a and being slotted as at 6 to receive projections 7 fixed to opposite sides of the body portion B. Each supporting bracket also carries the pivoted latches 8 which are actuated by the hand lever 9 through pull rods 10, said latches being pivoted at 11 and normally held in locking position by leaf springs 12. Said pull rods 10 are connected to levers 13 which are adapted to actuate the fingers 14, said fingers engaging the extremities 8' of the latches 8 when actuated, thereby depressing the latches to release the fixed projections 7.

As shown in Figures 5, 6, and 7, the hand lever 9 is fixed to a rocker shaft 15 which is rotatably mounted in threaded cup members 16 carried by threaded extensions 17 on the supporting brackets 5, said rocker shaft carrying the two pull rod actuating arms 18 and causing simultaneous operation of the latch members 8 when the hand lever is moved. This hand lever is retained by a resilient clip 19 in an out-of-the-way position along the side of the supporting bracket after releasing the latches.

The latch 3 for the side mirrors comprises a casing 20 which is slotted to receive a shiftable latch member 21 adapted to be actuated by a knob 22, said latch member being normally held in intermediate position by springs 23. The casing carries an extension 24 from which projects a loop 25 adapted to engage a lock 26 when the top is in lowered position.

With the vanity dresser in the position as shown in Figure 1, when it is desired to close it for use as a table, the side mirrors are swung toward each other against the center mirror, the latch being shifted to allow first one and then the other to become fully closed and held in position, the backing of these side mirrors constituting a protection for the large mirror and for the small mirrors as well when swung into this closed position. To lower the top, the hand lever is grasped with one hand and the other hand is placed along the edge of the top near the center to steady it. As the lever is pulled forward, disengaging it from the clip 13, the rocker arm is rotated causing the levers 18 to actuate the pull rods 10 and rotate the levers 13 about their pivots, thereby drawing the latch members 18 down into the recess in the supporting brackets, and allowing the supporting brackets to slide over the fixed projections 7 on the sides of the dresser as the top is lowered to closed position where it may be locked in said position by a key which may be inserted into the key hole 27 to actuate a lock 26 if so desired. The bench is then lifted and slid beneath the dresser where it is supported on a shelf 28, bringing the dresser in-

to the position shown in Figure 2 making it useable as an ordinary table.

To go from the position shown in Figure 2 to the position of Figure 1 merely requires the lifting of the top after unlocking the same, whereupon the supporting brackets will slide on the projections and automatically lock the top in a substantially vertical position where the latch 3 may be manipulated to release the side mirrors allowing them to be swung to the position desired. The bench may be drawn forward and placed in position in front of the dresser for use. The raising of the top renders all of the toilet articles readily accessible.

While the specific details of construction have been herein shown and described, the invention is not confined thereto as changes and alterations may be made without departing from the spirit thereof as defined by the appended claims.

Having thus described our invention, what we claim as new and desire to secure by Letters Patent is:

1. In an article of furniture, an enclosing body portion provided with a movable closure, said closure being shiftable to a substantially vertical position, a plurality of supporting brackets for retaining the said closure in said vertical position, latch means for the said supporting brackets, and manipulating means carried by one of the said supporting brackets for operating both of the said supporting bracket latch means.

2. In an article of furniture, an enclosing body portion, supporting means therefor, a shiftable closure member for said enclosing body portion and means for retaining the said closure member in open position, said means comprising a bracket member pivoted to said closure member and having a slot in one arm thereof, a projection carried by said enclosing body portion for engaging said slot, a latch pivotally carried by said bracket member, a spring engaging said latch for normally retaining the same in position for engaging the said projection, a lever pivotally carried by said bracket member and engaging said latch, a hand lever pivoted to said bracket member, and a pull rod connecting said hand lever to said latch engaging lever for permitting manipulation of the said latch by said hand lever.

3. In an article of furniture, an enclosing body portion, supporting means therefor, a shiftable closure member for said enclosing body portion, means for retaining the said closure member in open position, said means comprising a bracket member pivoted to said closure member and cooperating with said enclosing body portion, a latch carried by said bracket member, and means carried solely by said bracket member for manipulating said latch.

4. In an article of furniture, an enclosing

body portion, a shiftable closure member therefor, means for retaining said closure member in open position, said means comprising a pair of spaced bracket members pivoted to said closure member and cooperating with said enclosing body portion, a latch carried by each of said bracket members, and means adjacent one of said bracket members for manipulating the latches of both of said

10 bracket members simultaneously.

5. In an article of furniture, an enclosing body portion, a shiftable closure member therefor, means for retaining said closure member in open position, said means comprising a pair of spaced bracket members pivoted to said closure member and cooperating with said enclosing body portion, a latch carried by each of said bracket members, and means adjacent one of said bracket

15 members for manipulating the latches of both of said bracket members simultaneously, said means including a rocker shaft extending longitudinally of the said closure member and adjacent one edge thereof.

20 6. In an article of furniture, an enclosing body portion, a shiftable closure member therefor, means for retaining said closure member in open position, said means comprising a pair of spaced bracket members

25 pivoted to said closure member and cooperating with said enclosing body portion, a latch carried by each of said bracket members, and means adjacent one of said bracket members for manipulating the latches of both of said

30 35 bracket members simultaneously, said means including a rocker shaft pivotally mounted between said bracket members.

In testimony whereof we affix our signatures.
